Primary Examiner—Sandra L. Morris[57] **CLAIM**

The ornamental design for a lottery ticket accessory board, as shown and described.

DESCRIPTION

FIG. 1 is a front elevational view of the lottery ticket accessory board showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is a rear isometric view thereof.

The broken line showing of the indicia is for illustrative purposes only, and forms no part of the claimed design.
